UNITED STATES PATENT OFFICE.

GEORGE R. MOON, OF WILMINGTON, OHIO.

HEAT-EQUALIZER FOR OVENS.

SPECIFICATION forming part of Letters Patent No. 415,649, dated November 19, 1889.

Application filed May 9, 1889. Serial No. 310,107. (No model.)

To all whom it may concern:

Be it known that I, GEORGE R. MOON, a citizen of the United States, residing at Wilmington, in the county of Clinton and State of Ohio, have invented certain new and useful Improvements in Heat-Equalizers for the Ovens of Gas, Gasoline, and Oil Stoves; and I do declare the following to be a full, clear, and exact description of the invention, such as will enable others skilled in the art to which it appertains to make and use the same, reference being had to the accompanying drawings, and to the letters of reference marked thereon, which form a part of this specification.

The special object of the invention is to economize and equalize heat in gas, gasoline, and oil stove ovens, the trouble being with these ovens that they become too hot on the bottom and insufficiently so on the top.

Figure 1 is a perspective view of my improved heat-equalizer. Fig. 2 represents a vertical section of the equalizer, taken on line *x x* of Fig. 3. Fig. 3 is a vertical transverse section taken on line *z z* of Fig. 2. Fig. 4 is a vertical section of an oven with the equalizer in position therein, the latter being shown in vertical longitudinal section.

A designates the heat-equalizer, which is commonly constructed of sheet-iron, that being a good radiator of heat.

B indicates the lowest or first flue, which receives the heat directly from the burner through the opening *b*, and conducts it to the opposite sides of the oven. Next above the flue *B* is a flue *C*, and above the latter is a flue *D*, the two last-mentioned flues being for conducting to the sides of the oven heat generated by radiation. The said flues are preferably made in the form of an obtuse angle, inclining upward somewhat from the center to the sides of the oven, and narrowing to their extremities, the lowest flue *B* being the largest.

E indicates the side walls of the equalizer, which are provided with an opening *c*, which is intended for the admission of air into the flue *C*, there being a limited air-space surrounding the equalizer between the latter and the walls of the oven. The heat from the burner passes rapidly through the flue *B* to the sides of the oven, and rises to the top, as indicated by the arrows in Fig. 4. At the same time the heat produced by radiation from the bottom is conducted to the sides by the flues *C* and *D*. The heat rising at the sides of the oven causes the upper cool air to descend, and such cool air, passing through apertures *c* into the flue *C*, becomes heated and is conducted by said flue to the sides of the oven. Thus a continuous circulation is produced in the oven as long as there is any inequality in the temperature therein, so as to approximately equalize the heat in all parts of the oven, the heat being thus utilized to the best advantage.

I claim—

1. A heat-equalizer for an oven, constructed of sheet metal and provided with a flue which is constructed to receive the heat from a burner and conduct it to the sides of the oven, and an adjoining upper flue provided with openings *c* and constructed to convey radiating heat to the sides of the oven, substantially as and for the purposes described.
2. In a heat-equalizer of an oven, a lower flue extending in opposite directions from the center, and an adjoining upper flue provided with air-openings *c*, said flues being inclined upward and being tapered to their extremities, substantially as set forth and described.

In testimony whereof I affix my signature in presence of two witnesses.

GEO. R. MOON.

Witnesses:

F. HIATT,
JOE T. DOAN.
